UNITED STATES PATENT OFFICE.

JAMES C. MEWSHAW, OF BALTIMORE, MARYLAND.

EMERGENCY GASOLINE TANK.

Application filed November 3, 1922. Serial No. 598,802.

To all whom it may concern:

Be it known that I, JAMES C. MEWSHAW, a citizen of the United States, residing at Baltimore, in the county of Baltimore and 5 State of Maryland, have invented a new and useful Emergency Gasoline Tank, of which the following is a specification.

The present invention is an auxiliary or emergency gasoline tank to be carried by 10 automobilists in order that an extra amount of gasoline will be available in cases of emergency.

The object of the invention is to provide a tank of the above stated character 15 which can be conveniently carried, in spaces usually regarded as waste space, for instance under the seats, or in the pockets in the doors, or in the tool box, and it is of such size and dimensions as to permit 20 of this as well as the tank to be conveniently handled and its contents poured therefrom into ordinarily inaccessible places.

A further object of the invention is the production of an emergency gasoline tank, 25 as above stated, having a simple and inexpensive construction, which will withstand rough treatment.

Broadly stated, the features of the present invention reside in an elongated container or receptacle having a tapered neck 30 with a discharge opening therein, permitting the container to be inserted into rather inaccessible places and further causing an even and steady flow of its contents through the opening,—and in a funnel normally retained within the neck of the receptacle to be conveniently stored away and to strain the liquid placed therein, and which funnel can be removed therefrom, when the 35 contents of the receptacle are to be dispensed, for cooperation with the neck to facilitate the dispensation of the contents of the receptacle.

The invention further resides in sundry 40 details of construction, combinations and arrangements of parts as hereinafter further set forth.

In this specification and the annexed drawings, the invention is disclosed in the 45 form in which it is considered to be the best, but the invention is not limited to such form because it is capable of being embodied in other forms; and it is to be understood that in and by the claims following the description herein it is intended to cover the invention in whatever form it 50 may embody within the scope thereof.

In the drawings which disclose the preferred embodiment of the invention as at present devised,

Figure 1 is a side elevation of the aux- 60 iliary tank,

Fig. 2 is a longitudinal sectional view of the tank,

Fig. 3 is a perspective view of the tank in its liquid discharging position and illustrating the manner in which the funnel 65 operates therewith,

Fig. 4 is a top plan view of a modified form of the funnel,

Fig. 5 is a longitudinal sectional view of 70 the funnel shown in Fig. 4,

Fig. 6 is a top plan view of the container showing a modified form of closing cap,

Fig. 7 is a fragmentary side elevation of the container equipped with the modified 75 form of cap shown in Fig. 6.

Fig. 8 is a fragmentary side elevation of the emergency tank having a further modified form of closing cap,

Fig. 9 is a longitudinal sectional view 80 taken substantially on line 9—9 of Fig. 8,

Fig. 10 is an enlarged plan view of the former cap shown in Figs. 8 and 9, and

Fig. 11 shows a modified form of the emergency gasoline tank shown in Figs. 85 1 and 2.

Referring particularly to the drawings in which like characters denote similar parts throughout the several views, 1 indicates an elongated tubular barrel of substantially the proportions shown in the drawings. While a cylindrical container is shown, it may be of any other desired form such as rectangular or polygonal in cross section. One end of the container is closed as at 2 to form the bottom and its other end is, preferably, conically shaped forming a relatively long tapered neck 3. The outer end portion of the neck 3 is preferably shaped in the form of a cylinder, as at 4, and has tightly fitted on its outer face an annular collar 5 which is externally threaded. The collar 5 is made rigid with the neck 3 in any suitable manner such as by shrinking, sweating or other equivalent ways known to the mechanic.

The upper or outer edge of the collar 5 extends slightly above the outer edge of the neck 3 to provide a shoulder 6. This shoulder is to support and retain in the neck of the receptacle a funnel 7 which is formed on its upper or enlarged end with a corresponding flange 8 to rest upon the shoulder. It is, of course, understood that the

collars 5 may be dispensed with by threading the cylindrical extension 4 of the neck and internally rabbetting the top edge to provide the shoulder 6.

5 The receptacle is closed by a cap 9 having a downwardly extending peripheral flange 10 internally threaded to engage the threads on the collar 5. A suitable washer or gasket 11 is provided between the cap and the discharge end of the receptacle to insure a tight water-proof joint. It will thus be seen that with the parts in assembled position, as shown in Fig. 2, and the container closed, the funnel 7 will be maintained wholly within 10 the confines of the receptacle against movement or rattling.

When it is necessary or desirable to dispense the contents of the receptacle the cap 9 is removed and the funnel 7 withdrawn 20 through its mouth. It will be obvious that on account of the shape of the receptacle it may be inserted into inaccessible places to dispense its contents and the funnel 7 may be used as shown in Figure 3 in order to confine and direct the liquid to the place desired.

25 The tank 1 may be drawn or otherwise formed from metal so that the bottom 2 and the neck 3 may be integral therewith but the bottom and the neck portions may be separate parts, as may be found more desirable in practice.

30 In Figs. 4 and 5 a modified form of funnel is illustrated, the same reference characters being used as in the foregoing embodiments 35 to designate corresponding parts, except that these reference characters are raised by the exponent "a". This modified form of funnel is identical in all respects to the type shown in Figs. 1, 2 and 3, with the addition 40 that it is provided with a screen or strainer 12 for the purpose of collecting any dust, dirt or foreign particles which may be in the gasoline or other liquid contained in the tank.

45 When using the modified form of funnel 7^a, the funnel has a two-fold purpose: First, for screening the gasoline or the like when the receptacle is being filled, and secondly, for screening the same when it is being discharged from the receptacle into the vacuum tank or other desired portion of the automobile, or other container. Thus with the present emergency tank equipped with the form of funnel shown in Figs. 4 and 5, the 50 gasoline is subjected to a double straining or filtering treatment, because the funnel is normally in the mouth or neck of the tank as in Fig. 2, when re-filling the tank, and when it is desired to dispense the liquid the 55 funnel 7^a is removed and used in the manner shown in Fig. 3.

60 In Figs. 6 and 7 a modified form of closing cap is shown wherein the peripheral edge of the cap is formed with cut out or notched 65 portions 13, which can be easily grasped and

will facilitate the removing of the cap 9^a or its application tightly in place.

In Figs. 8, 9 and 10, a still further modified form of cap is shown wherein the threaded connection is eliminated and can 70 be used with any shaped discharge opening. The same reference characters employed in Figs. 1, 2 and 3 are used in referring to this embodiment except that the reference characters are raised by the exponent "b". In 75 this form the collar 5^b is provided on its upper edge with two bayonet slots 14. The cap consists of flat disk-like member 9^b, see Fig. 10, having pivotally secured thereto a leaf spring 15, having its ends extending beyond the periphery of the cap in opposite directions, so that when the cap 9^b, being of a size to tightly fit into the collar 5^b, as shown in Fig. 9, is inserted in position in 80 the discharge opening of the receptacle, the arms X of the spring will engage in the bayonet slots, as shown in Fig. 8, and tightly maintain the cap in position, there being a gasket 11^b between the cap and the funnel 7^b.

85 A still further modified form of the invention is shown in Fig. 11, wherein a double container 16 is provided having an elongated formation, the same as shown in Figs. 1, 2 and 3. This double receptacle is divided at a point in its length by a partition 17, 90 thus forming two compartments 18 and 19, preferably one for gasoline or other liquid fuel, and the other for oil or other lubricating liquid. Both ends of the container are 95 conically formed the same as shown in Figs. 1, 2 and 3, to provide tapering discharging necks 20, closed by the caps 21 threaded thereon. Funnels 22 are provided in each 100 of the discharge necks similarly as shown in the other embodiments of the invention. As 105 the form of the invention shown in Fig. 11 is otherwise similar to the construction of the tank shown in the Figures 1, 2 and 3 of the invention, it is believed that no further 110 description will be necessary.

The emergency gasoline tanks according to this invention are made of substantially heavy gage metal such as brass, steel, iron or the like, so that the same will stand rough usage, and will not become easily bent or 115 punctured.

Having thus described the invention in its preferred embodiment as at present devised, what is claimed as new and upon which Letters Patent is desired, is:

120 1. An emergency gasoline tank of the kind described comprising a container composed of relatively thin stock provided with a discharge opening having its marginal edge portion extended outwardly, a threaded collar surrounding said marginal portion and fittedly mounted thereon and of relatively heavier stock permitting it to be threaded with a cut thread, the edge of the marginal portion providing a shoulder upon which a 125 130

funnel or the like may rest, and a closure cap correspondingly threaded for engaging said collar to close said opening and hermetically seal the tank.

- 5 2. An emergency gasoline tank of the kind described comprising an elongated barrel having an outwardly tapering neck of relatively thin stock, the outer end of said neck being provided with a discharge opening,
- 10 the marginal edge portion of which is extended at an angle to the neck portion and parallel to the longitudinal axis of the barrel, an annular collar of relatively heavier stock surrounding said marginal portion of
- 15 the neck and fittedly mounted thereon, said collar being externally threaded, the edge of the marginal portion of the neck terminating below the outer edge of said collar to provide an internal shoulder within said
- 20 discharge opening, a funnel removably disposed in said neck portion and having a

flange thereon to rest on the said shoulder, and a cap closure threaded correspondingly with said collar to close said opening and normally retaining the funnel in position 25 within the confines of the container.

3. An emergency gasoline tank of the kind described comprising a container composed of relatively thin stock and provided with an opening therein, an externally 30 threaded collar of heavier stock surrounding said opening, a funnel disposed and supported for storage carrying purposes in said opening and removable therefrom for cooperative use with the tank when discharging 35 the contents thereof, and a cap engaging the collar to close and hermetically seal said opening with said funnel in position therein and within the tank.

In testimony whereof I have hereunto set 40 my hand.

JAMES C. MEWSHAW.
